ROY A. RODGERS, OF SENECA, KANSAS, ASSIGNOR OF ONE-THIRD TO JACOB H. HARRISON, OF FALLS CITY, NEBRASKA.

COMBINED MOP AND WRINGER.

1,142,628.

Specification of Letters Patent. Patented June 8, 1915.

Application filed September 19, 1914. Serial No. 862,591.

To all whom it may concern:

Be it known that I, ROY A. RODGERS, a citizen of the United States, residing at Seneca, in the county of Nemaha and State 5 of Kansas, have invented a new and useful Combined Mop and Wringer, of which the following is a specification.

This invention has reference to a combined mop and wringer, and its object is to 10 provide means whereby surplus water may be squeezed out of the mop by the simple expedient of pulling the mop between rollers under constant tension.

In accordance with the present invention 15 there is provided a mop head in which two rollers are mounted, one being under a constant spring tension tending to hold it in engagement with the other roller, but the roller under spring tension is movable away 20 from the other roller to permit the insertion of the mop which is provided at the ends with clip members readily applied to and removed from the handle of the mop. In this way the mop may be drawn in 25 either direction between the rollers, but at no time is it drawn completely through the mop head and that roller which is the more distant from the handle is in position to bear against the mop cloth when the latter 30 is in use.

The invention will be best understood from a consideration of the following detailed description, taken in connection with the accompanying drawings forming a part 35 of this specification, with the further understanding that while the drawings show a practical form of the invention, the latter is not confined to any strict conformity with the showing of the drawings, but may be 40 changed and modified so long as such changes and modifications mark no material departure from the salient features of the invention.

In the drawings, Figure 1 is a side elevation of the mop head with the mop in place, some parts being broken away and in section. Fig. 2 is a view similar to that of Fig. 1 but with the mop cloth removed, and also showing some parts broken away and in 50 section. Fig. 3 is an end elevation of the structure of Fig. 1 with some parts in section. Fig. 4 is a perspective view of one of the arms making up the frame of the mop head. Fig. 5 is a perspective view of a

spring member. Fig. 6 is a perspective view 55 of a connecting link.

Referring to the drawings, there is shown a handle 1 which may be assumed to be of suitable length, and which is usually made of wood. Fast to and projecting in opposite directions from opposite sides of one end of the handle 1 are angle arms 2, each having at one end a short angle extension 3 fitted against the corresponding side of the handle 1 and there held by a screw 4, or in 60 any other appropriate manner. Each arm 2 is of sufficient length to offset an appropriate distance from the handle 1 and at the outer end has another angle extension 3^a substantially parallel with but oppositely 65 directed with respect to the extension 3. The extension 3^a is provided near the arm 2 with a perforation or passage 5 and at the extremity with an entering slot 6 lengthwise of the extension 3^a. 75

Mounted in the perforations 5 are the pintles 7 of a roller 8, the latter being of sufficient length to reach from one extension 3^a to the other.

Mounted in the entering slots 6 are bearing members or pintles 9 at opposite ends of another roller 10. The pintles 9 are shown as in the form of suitably headed screws, but other devices than screws may be employed for the purpose. There are also provided leaf springs 11 with oppositely directed angle extensions 12 and 13, respectively, at opposite ends. The extension 12 of each spring 11 is secured against the extension 3 of a corresponding arm 2 and a screw 14 80 extending through suitable perforations in the extensions 12 and 3 serves to hold the spring 11 to the handle 1 and also constitutes an additional means for securing the arm 2 thereto. Passed through a perforation 15 in the extension 13 of the spring 11 is a hook 16 formed on one end of a link 17, the other end of which is formed into an eye 18. The link 17 is arranged outside of the extension 3^a of the corresponding arm 2 85 and the eye 18 is engaged by the screw 9, which latter may be provided with a suitable head serving to hold the eye 18 to the screw. The arrangement is such that the tendency of the springs 11 acting through 90 the link 17 is to hold the roller 10 against the roller 8 with an appropriate force, but a suitable force tending to move the roller 95 100 105

10 away from the roller 8 will cause the springs 11 to yield to permit such movement of the roller 10 and when the force is removed the springs 11 at once return the 5 roller 10 toward the roller 8. There is also provided a mop cloth 19 which may be of the usual elongated endless web type, and through opposite ends of the mop cloth 19 loops or bails 20, which may be formed of 10 wire, are passed. These loops are of general elongated rectangular form and midway of the side of each loop remote from the mop cloth there is formed a short bend 21 with the side approximately parallel. 15 The bend 21 offstands from the body of the loop and is long enough to engage under the heads of two closely associated headed screws 22 carried by the handle 1 and spaced apart in the direction of the length of the 20 handle, a pair of screws being on one side of the handle and another pair of screws on the opposite side, so that each loop 20 is in general parallel with the axis of rotation of the roller 8. Each loop or bail is 25 of a length to reach from the handle to a point opposite the center of the first roller, and as shown in Fig. 3, is given a spring tendency inwardly so as to hold the mop cloth against said roller. The bend 21 may 30 have its sides slightly closer together nearer to the loop 20 than at the yoke end of the bend, so as to be held by the screws 22 with some little force resistant to removal.

One side or run of the mop 19 is passed 35 between the rollers 8 and 10. Suppose now that the mop cloth 19 is dipped into water and thereby becomes wet and too wet for use, and it is desired to remove surplus water. The user removes that loop 20 carrying the part of the mop cloth close to 40 where it extends between the rollers, and by a pulling movement the mop cloth is caused to move between the rollers, thus squeezing out surplus water and the movement is continued until arrested by the other 45 loop 20 still fast to the handle 1. The result is that the greater portion of the mop cloth has been wrung sufficiently dry, whereupon the removed loop 20 is returned 50 to position and the mop is ready for use. In using the mop, pressure is applied thereto directly by the roller 10 which is held against rotation during the use of the mop 55 by the frictional engagement of the mop cloth therewith. It will be observed that the working face of the roller projects beyond the outer end of the arms, so that only the roller comes in contact with the mop cloth. When it is again desired to wet the 60 mop for cleansing and other purposes, it is simply needful in order to dry the mop to reverse the operation already described. It is quite possible to pull the mop cloth through the squeezing rollers without re- 65 moving either loop 20, but the loop forms a

convenient hand-hold facilitating the drawing movement of the mop cloth between the pair of rollers.

Wood or metal may be employed as the materials out of which the rollers are constructed, or they may follow the usual practice in clothes wringers, where a rubber surface is provided.

The structure is one of extreme simplicity and compactness, and may be made of light 75 weight without sacrifice of strength or advantages. There is nothing in front of the outer roller to take up any of the mop cloth, and, therefore, a greater amount of the cloth may be used than in structures 80 where there is a bar or other device in front of the outer roller. Again, the front or outer roller is readily removable at any time without disturbing any of the other parts of the structure.

The loops or bails forming the hand holds are held firmly by the bend and the screws against any swinging movement in any direction, while the mop is in use, and these hand-holds being as wide as the mop 90 causes the cloth to pass evenly between the rollers, for the opposite end is held directly in front of and against the upper roller 8.

The facility with which the outer roller 95 may be removed and when needed the inner roller may be removed are important and distinguishing features of the present invention.

What is claimed is:—

1. A mop structure comprising a handle, angle arms fast to and projecting from opposite sides of one end of the handle, said arms being provided at the ends remote from the handle with an entering slot and a perforation spaced from the inner end of said slot, a roller journaled in the perforations, another roller having pintles entering the slots and projecting therefrom, leaf springs fast to the handle and projecting over the angle arms, and links carried at one end by the outer end of a respective leaf spring, and each formed at the other end into a loop receiving the pintle at the respective end of the second-named roller, said links being arranged on the outside of and alongside the arms and adapted to hold the said roller with its working face extended beyond the horizontal plane of the outer ends of said arms, whereby only the 110 roller contacts with the mop cloth.

2. A mop structure comprising a handle, supporting arms carried thereby, a pair of rollers mounted in said arms in superimposed relation, a mop cloth extending between the rollers, wire bails at the opposite ends of the mop cloth, each bail comprising a loop having one portion thereof traversing the respective end of the mop cloth, and the opposite portion formed intermediately 125 130

into a short bend with the sides approximately parallel, headed fastening means mounted on the handle and adapted to receive the said bend of the bail, each bail 5 being of a length to reach from the handle to a point opposite the first roller and having an inward spring tendency to hold the mop cloth against said roller.

In testimony, that I claim the foregoing as my own, I have hereto affixed my signature in the presence of two witnesses.

ROY A. RODGERS.
